UNITED STATES PATENT OFFICE.

JOSEPH BOCK, SR., OF CINCINNATI, OHIO.

SOAP COOLER AND COMPRESSOR.

1,271,657.

Specification of Letters Patent.

Patented July 9, 1918.

Application filed December 17, 1915. Serial No. 67,352.

To all whom it may concern:

Be it known that I, JOSEPH BOCK, SR., a citizen of the United States, and a resident of the city of Cincinnati, in the county of 5 Hamilton and State of Ohio, have invented certain new and useful Improvements in Soap Coolers and Compressors, of which the following is a full, clear, and exact description, reference being had to the accompanying drawings, forming part of this specification.

My invention has relation to machines for the purpose of cooling and compressing soap in one operation, and turning it out of the 15 machine in bars of the proper cross-sectional area to be cut or stamped into hand cakes of soap.

It has as its object the providing of a cylinder wherein the soap when in liquid condition from the crutcher is to be poured, pressure devices automatically controlled to put the soap under pressure while in the cylinder, and a progressive cooling system whereby the soap during its progress 25 through the cylinder under pressure will be gradually cooled down, and finally pressed out through a die plate in the form of a long bar of proper cross-sectional area, as above mentioned. It will be understood that the 30 soap is very hot when it comes from the crutcher, but that it should not be brought at once into contact with a very cold medium. To be properly compressed and ready to cut into cakes, however, it must 35 contain none of the heat of the saponification process. Ordinarily the soap from a crutcher is formed up into a large block and this is allowed to cool and dry out for a considerable length of time, with a consequent 40 loss in manufacturing efficiency. My new machine is designed to accomplish this operation of cooling, and compressing and cutting in a comparatively short time and without the necessity of handling and cutting 45 large blocks of soap.

The objects detailed I accomplish by that certain construction and arrangement of parts to be hereinafter more specifically pointed out and claimed.

50 In the drawings,

Figure 1 is a front elevation of the machine.

Fig. 2 is a central, longitudinal vertical section thereof, with the piston removed.

55 Fig. 3 is a perspective view of the die plate.

The cylinder 1, preferably supported vertically on standards 2, 2, has an inlet funnel 3 through which the soap from the crutcher (not shown) is poured. Mounted at the upper end of large supporting arms 4, 4, bolted to the upper end of the cylinder is a thrust bearing 5, which forms a bearing for an interiorly screwthreaded sleeve 6. On this sleeve at the base is a worm gear 7, which is 60 in mesh with a worm gear 8 on the shaft of a motor 9. This motor is mounted on the bracket 10 which is secured in any desired manner to the supporting arms.

65 Mounted so as to reciprocate in the cylinder is a piston 11, that serves to compress the soap and force it out of the other end of the cylinder as will be described. The piston is attached to a long shaft 12, that is screwthreaded and passes through the 70 sleeve 6. A proper stuffing box 14 bolted to the end of the cylinder receives the shaft 12 which has a long key 13 that slides in a feather in the box, so that the shaft can slide but cannot turn in the said box. When 75 the motor is running, therefore, the sleeve 6 will cause the shaft 12 to move slowly and with great pressure downwardly or upwardly, forcing the piston down into the cylinder and properly compressing the 80 contents thereof.

85 A series of separate jackets are provided along the length of the cylinder, adapted to receive cooling water and brine of progressively varying degrees of coldness. The top- 90 most water jacket 16, having the inlet 17 and the outlet 18, is to be used with cold water as it comes from the usual outside water supply. The jacket 19 having the inlet 20 and the outlet 21 is to receive brine 95 at about thirty degrees Fahrenheit. The next jacket 22, with inlet 23 and outlet 24, is to receive brine at, say, twenty-five degrees Fahrenheit.

100 At the base of the cylinder is securely attached the delivery nozzle section 25, which turns at a right angle to the cylinder in order to deliver the soap on a horizontal plane. The section of the nozzle is water jacketed at 26, and is supplied with brine at, say, 105 twenty two degrees Fahrenheit, through the inlet and outlet 27, 28, respectively.

110 There are two sections of the nozzle between which is the die plate 29 which is of a size to be inserted in a slot 30 formed between the two sections. All the soap forced through the cylinder is pressed out through

this die plate, which has, say, three apertures 31, of the desired cross-sectional area. The soap from the die plate passes out through the end section 32 of the nozzle 5 which forms a wide, shallow passageway of the correct thickness for the bars of soap formed in the die, and is bolted onto the other portion of the nozzle and formed as is the other nozzle section so as to leave the 10 slot 30 above referred to. This extended end of the nozzle is waterjacketed at 33 and brine is sent through the jacket, through an inlet and an outlet 34 and 35 respectively, at a temperature of about seventeen degrees 15 Fahrenheit.

At the beginning of an operation the cylinder is filled with soap, say, about one thousand pounds, or as much as a crutcher will hold, and the brine started gradually 20 through the jackets, at the same time starting the motor. At the delivery end of the nozzle is an endless belt support 36 of a cutting machine on which the soap is delivered of the desired length, say, four feet. As 25 soon as four feet of soap has been forced out over the belt of the cutting machine, which will move as the soap is forced out onto it, the soap will come in contact with a circuit breaking switch contact member 37, which 30 will be pushed over by the soap, and held there until the pusher 38 of the cutter pushes the soap past the usual cutting wires and off of the belt and returns to its normal position, the pusher itself holding the breaker open. 35 The breaker switch then automatically closes and the motor continues to push out soap and the pusher is operated until the piston gets well down in the cylinder.

The piston will force about two-thirds of 40 the contents out of the cylinder, leaving one-third in the base of the cylinder and the nozzle portions. When it has reached this point, the piston screw throws a switch 39 that cuts off the current from the motor. The motor is 45 then reversed, the piston raised and another charge put in. The cylinder is large enough to hold the charge of a crutcher in addition to the amount in the cylinder base and the nozzle portions. Accordingly after the operation 50 is begun, there will be a constant charge of cooled and compressed soap in the nozzle, and there will never be such a rapid cooling of the upper portions of the soap mass, to prevent the even application of pressure in the base of the cylinder by premature hardening.

By the die plate, the soap will be formed into long bars of the correct cross-section and delivered out onto the table or endless belt, 60 where it will shut off the motor from time to time. This progressive movement of the soap takes a considerable time, preferably fifteen minutes for a crutcher full, which is requisite for best results, and it can readily be seen that the adjustment of the length of 65

the delivered bar and the worm and screw at the upper end of the machine will give any desired time for each portion of soap to pass completely through the entire operation.

No cutting devices have been shown, but 70 it will be understood that some means for cutting up the long bar of soap will best be used, against which the pusher will operate in the usual manner.

The cylinder is a large one, say, six feet 75 long and twenty-two inches in internal diameter, and a great deal of work can be turned out by it in a time comparatively very short as compared with the processes now in common use. Various modifications might well 80 be made without departing from the spirit of my invention, and I desire in the claims that follow to include the full range of equivalent structures for the elements set forth, although for the sake of brevity no 85 attempt has been made to set out equivalents while describing the invention in detail.

The time of operation is to be proportioned to the time that it takes for the preparation of a crutcher of soap. Two-thirds 90 approximately of each crutcherfull will be delivered and cut at each operation, and the machine will take a crutcherfull at each charge.

Having thus described my invention, what 95 I claim as new and desire to secure by Letters Patent, is:—

1. In a device of the character described, a cylinder for soap, a series of separate and independent water jackets around said cylinder adapted to receive cooling media of progressively lower temperatures ranging from the receiving end to the delivery end, a nozzle at the delivery end and a die plate in the nozzle, said die plate being provided 100 with an aperture of a cross sectional area to form the soap into bars of the shape and size desired, a piston in the cylinder, and means for operating the piston slowly to force the soap through the cylinder without 105 agitation, whereby disintegration of the soap is avoided.

2. In a device of the character described, a cylinder for soap, a series of separate and independent water jackets around said cylinder adapted to receive cooling media of progressively lower temperatures ranging from the receiving end to the delivery end, a nozzle at the delivery end and a die plate in the nozzle, said die plate being provided 115 with an aperture of a cross sectional area to form the soap into bars of the shape and size desired, a piston in the cylinder, and means for operating the piston slowly to force the soap through the cylinder without 120 agitation, whereby disintegration of the soap is avoided, with means providing a movable surface adapted to be operated by the bars as they leave the nozzle to receive and hold 125 said bars.

3. In a device of the character described, a vertical cylinder for soap, a series of separate and independent water jackets around said cylinder adapted to receive cooling media of progressively lower temperatures ranging from the receiving end to the delivery end, a nozzle at the delivery end turned at right angles to the cylinder, and a die plate in the nozzle, said die plate being pro-

vided with an aperture of a cross sectional area to form the soap into bars of the shape and size desired, a piston in the cylinder, and means for operating the piston slowly in the vertical portion of the cylinder to force the soap through the cylinder without agitation, whereby disintegration of the soap is avoided.

JOSEPH BOCK, Sr.
